ABSTRACT

A tunneling machine having a form transfer and handling device comprising a truss which extends longitudinally of the tunnel, said truss having legs which support the truss from the tunnel floor, the space about the truss being substantially unobstructed except in the vicinity of the legs, a trolley movable along the truss, and a form carrier on the trolley to pick up form sections from near the rear end of the truss and convey them in said unobstructed space toward the head end of the tunnel.

CROSS REFERENCE TO RELATED APPLICATION

This application is a division of copending U.S. patent application Ser. No. 743,363 filed July 9, 1968, now U.S. Pat. No. 3,561,223 granted Feb. 9, 1971, the entire disclosure of which is incorporated herein by reference.

SUMMARY OF THE INVENTION

The invention relates to a tunneling machine having a form transfer and handling device comprising a truss which extends longitudinally of the tunnel, said truss having legs which support the truss from the tunnel floor, the space about the truss being substantially unobstructed except in the vicinity of the legs, a trolley movable along the truss, and a form carrier on the trolley to pick up form sections from near the rear end of the truss and convey them in said unobstructed space toward the head end of the tunnel. The truss has rails on which the trolley rides. The trolley has a hollow center through which the truss extends and rotatably carries a form handler which shifts forms from the bottom of the truss to the top of the truss.

DESCRIPTION OF THE DRAWINGS

FIGS. 1-22, inclusive, are illustrated and described in said U.S. Pat. No. 3,561,223.

In the attached drawings;

FIG. 14 is a vertical longitudinal section taken through the tunnel and showing in elevation the form handler mounted on the truss.

FIG. 15 is a cross section taken along the line 15-15 of FIG. 14.

FIG. 16 is a cross section taken along the line 16-16 of FIG. 14.

FIG. 17 is a cross section taken through the tunnel and showing the form handler in the course of handling a partially collapsed top form section.

FIG. 18 is a similar cross section showing the form handler in the course of handling a partially collapsed bottom form section.

FIG. 19 is a side elevation of the form handler, a portion of this view being shown in vertical longitudinal section.

**DESCRIPTION OF THE PREFERRED
EMBODIMENT**

Although the disclosure hereof is detailed and exact to enable those skilled in the art to practice the invention, the physical embodiments herein disclosed merely exemplify the invention which may be embodied in other specific structure. The scope of the invention is

defined in the claims appended hereto.

The entire disclosure of said U.S. Pat. No. 3,561,223 is incorporated herein by reference. Particular attention is invited to FIGS. 2, 14, 15, 16, 17, 18, 19, 20, and 22, and to the accompanying description.

I claim:

1. In a machine of the character described, a form transfer and handling device comprising a truss which extends longitudinally of the tunnel, said truss having legs which support the truss from the tunnel floor, the space about the truss being substantially unobstructed except in the vicinity of the legs, a trolley movable along the truss, and a form carrier on the trolley to pick up form sections from near the rear end of the truss and convey them in said unobstructed space toward the head end of the tunnel, said truss having rails on which the trolley rides, said trolley having a hollow center through which the truss extends, said trolley having bearings on which said form carrier is rotatable to shift forms about said truss from beneath the truss into said unobstructed space.

2. In a machine of the character described, a form transfer and handling device comprising a truss which extends longitudinally of the tunnel, said truss having legs which support the truss from the tunnel floor, the space about the truss being substantially unobstructed except in the vicinity of the legs, a trolley movable along the truss, and a form carrier on the trolley to pick up form sections from near the rear end of the truss and convey them in said unobstructed space toward the head end of the tunnel, said unobstructed space being at the top and sides of the truss, said forms comprising top form sections and bottom form sections, said trolley further comprising form carrier means to selectively carry either a top form section or a bottom form section, and means to rotate said form carrier means to transfer a bottom form section to a position at the top and sides of the truss in substantial alignment with said unobstructed space and convey it through said space to the head end of the tunnel.

3. In a machine of the character described, a form transfer and handling device comprising a truss which extends longitudinally of the tunnel, said truss having legs which support the truss from the tunnel floor, the space about the truss being substantially unobstructed except in the vicinity of the legs, a trolley movable along the truss, and a form carrier on the trolley to pick up form sections from near the rear end of the truss and convey them in said unobstructed space toward the head end of the tunnel, said trolley having a hollow interior within which the truss is received, said truss having tracks on which the trolley is movable longitudinally along the truss, said trolley having a form carrier rotatable thereabout to shift forms from the bottom of the truss to the top of the truss.
